SHAKING CONVEYER

Heinrich Grube, Bochum, Germany, assignor to
 Gebr-Eickhoff, Maschinenfabrik und Eisen-
 gesserei, Bochum, Germany

Application June 11, 1936, Serial No. 84,761
 In Germany July 5, 1935

10 Claims. (Cl. 198—220)

My invention relates to shaking conveyers and has particularly reference to the connecting members of the conveyor trough, and in particular to an interconnection of the type in which the connecting attachments abut against one another by cylindrical contact surfaces under the action of a locking or tightening member, so that the conveyor sections are capable of taking a mutual angular position in a vertical plane.

5 In a known construction of this type the trough connections are arranged beneath the trough and are hingedly connected by a bolt arranged transversely to the working direction of the trough and consequently this bolt is subjected to very high bending stresses. In another known connection of shaking conveyers the connecting means is formed by a transverse bar fixed to the underside of each element the both ends of which bar laterally project beyond the conveyor sections, one of these bars carrying on either end a pivoted U-shaped yoke adapted to be swung over the respective end of the bar of the adjacent section, the two co-operating transverse bars being locked in position by wedge mounted 15 on said yoke and adapted to be fixed between the two bars. Curved contact surfaces on the wedge and the ends of the bars enable a certain angular mutual displacement of the conveyor elements in a vertical plane. In this construction no direct transmission of power takes place between the two bar ends, but the forces passing from the one bar to the companion bar are transmitted through the wedge, whereby in connection with the possibility of the angular displacement of the sections an angularly broken transmission of the forces is caused from one bar to the other. Furthermore, such transverse connecting bars can be used only for conveyor section of one sole determined width. Finally 20 the arrangement of the connecting transverse bars on the underside of the conveyor elements as also the first described construction suffer from the drawback that the power is transmitted from one conveyor section to the other at a corresponding high level above the center of gravity of the cross section of the conveyor whereby a correspondingly great power moment is exerted upon the sheet metal plates of the conveyor sections.

25 In contrast to these known constructions, in the connection of conveyor sections according to my present invention the connecting attachments are provided on the side wall of the sections and protrude beyond them in transverse direction. The attachments are formed with cylindrical contact surfaces which extend horizontally and transversely of the working direction of the conveyor and are immediately pressed against one another by a tightening member disposed in parallel with the working direction of the conveyor,

In this new construction the connecting attachments can be situated at such a level on the side wall of the conveyor sections, that the passage of the power from one section to the other takes place at or approximately at the level of the center of gravity of the cross section of the troughs without a power moment being exerted upon the sheet metal plates of the sections. Furthermore, a fin-like shape can be given to the attachments, so that, likewise in contrast to the known constructions, a preserving gradual transition of the conveyor forces from the attachments to the sheet metal plates of the sections is obtained.

If the running wheels of the conveyor are mounted on the attachments in a manner known as such, the arrangement of the latter on the side walls of the sections affords a further advantage in so far as the conveyor then has a very small structural height, when compared with the constructions in which the running wheels are combined with connecting attachments arranged on the underside of the conveyor sections.

Furthermore the fact, that the two co-operating connecting attachments directly abut against one another by their cylindrical contact surfaces, results in a more favorable transmission of the power from one connecting element to the companion element, in comparison with the above-mentioned known construction, and further, likewise in contrast to the said known construction, the conveyor forces can be transmitted immediately, that means, without being spaced from the wall of the elements, directly along this wall.

The tightening member serving to interconnect the co-operating attachments may be of any suitable construction, as described herein-after in detail.

In order that my invention may be clearly understood and readily carried into effect, some embodiments of the same are illustrated in the accompanying drawings by way of example, the drawings representing various examples both of the construction of the connecting attachments and of the tightening member. In these drawings

Figure 1 is a side elevation of the first embodiment,

Figure 2 is a horizontal section thereof, and

Figure 3 is a vertical section thereof, while

Figure 4 is a front view of a connecting attachment.

Figure 5 shows another embodiment in horizontal section,

Figure 6 shows a third embodiment in side elevation,

Figure 7 is a top view thereof, and

Figures 8 and 9 are, respectively, views of a

fourth embodiment in side elevation and sectional top view.

My improved connection of conveyer sections substantially consists of two attachments *a* and *b*, preferably welded to the outside of the side walls of the conveyer section *r* and extending transversely of this wall, these attachments under the action of a tightening member abutting against one another by means of cylindrical surfaces *c* and *d* which extend horizontally and transversely of the working direction of the conveyer. As clearly to be seen in the drawings, the attachments may have a fin-like shape, that means, they may have a cross section decreasing 10 in width or height or both in width and height from their confronting ends, so as to have a correspondingly tapering rear end, and, consequently, they transmit to the plates of the conveyer sections forces which decrease according 15 to these decreasing cross sections. The transmission of the forces to the sections thus takes place without sudden transition, and in a preserving gradual manner.

The attachments *a* and *b* are connected to one another by a tightening member arranged when in operative position in parallel with the working direction of the conveyer and hingedly mounted on the attachments *a* which for this purpose are bifurcated. In the embodiments according to 25 Figures 1 to 7 the tightening member is formed by a screw bolt *e* hinged to the attachment *a*, so as to be swung in a vertical plane, and adapted to engage an eye *f* of an inverted U-shaped cross section provided on the attachment *b*. In order 30 to secure the nuts *g* in tightening position, the eye *f* is provided with a small nose *h*, see Figures 1, 2, 5, and 7, by which the bolt *e* and the nuts *g* are protected from being swung downward.

As shown in Figures 1 to 4, the bolt *e* may be 40 arranged for swing motion in a vertical plane only or both in vertical and horizontal planes or it may be arranged for ball joint motion, as shown in Figure 5. In this latter case the eye *f* is inclined on its outside in such a manner, that 45 when the tightening bolt has been swung into the position shown in Figure 5, the conveyer section which carries the attachment *b* can be lifted from the other element.

As illustrated in Figures 6 and 7, the bolt *e* can 50 also be articulated in itself for example at *i* as shown.

In the embodiment shown in Figures 8 and 9 the tightening member is formed by a U-shaped yoke *k* pivotally mounted on the attachment *a* 55 for vertical and horizontal swing motion. The yoke *k* has mounted on it a screw wedge *m* abutting against an extension *b'* of the attachment *b*, and when wedge *m* is tightened, it presses the cylindrical surface *d* of the attachment *b* against 60 the cylindrical counterface *c* of the attachment *a*.

In the embodiment illustrated in Figures 5 to 9 in which the tightening member is mounted for swing motion in a horizontal and vertical plane or is provided with a ball joint, the advantage is 65 obtained that each two adjacent conveyer sections are capable of positioning themselves angularly to one another in a vertical plane within certain limits, so that the conveyer can be adapted to a corresponding extent to the unevennesses of 70 the floor.

In all my new constructions of shaking conveyer connections the pivot axis *n* of the tightening member *e* or *k* may simultaneously form a journal for the running wheels *o* of the conveyer, 75 as illustrated in Figures 1, 3, and 5 by way of

example. Furthermore, in all these constructions that part of the attachment *a* or *b* which carries the tightening member can be disposed at such a level on the side wall of the conveyer section, that the tightening member is situated at least approximately at the level of the center of gravity of the whole cross section of the conveyer trough and, consequently, the forces are transmitted within the conveyer from one section to the other at least approximately at the level of 10 said center of gravity and thus without exerting a moment of force on the conveyer trough. Since the tightening members *e* or *k* are arranged in parallel with the longitudinal direction of the conveyer, they are stressed by the forces to be 15 transmitted by them in a very favorable manner, that means, they are subjected to traction only. Finally, the co-operating contact surfaces *c* and *d* of the connecting attachments are situated close to the side wall of the conveyer trough, which is 20 likewise favorable for the transmission of the forces.

What I claim and desire to secure by Letters Patent is:—

1. Means for interconnecting the sections of 25 shaking conveyers comprising an attachment secured to each side wall of a conveyer section at one end thereof, and another attachment secured to each side wall at the other end of the conveyer section co-operable with said first-named attachments of the adjacent element respectively, said attachments extending transversely of said walls and having curved complementary bearing surfaces engaging each other, the axis of curvature of said surfaces extending horizontally and 30 transversely of the direction of movement of the conveyer, and a member provided on both sides of said sections and adapted to exert a force in the direction of movement of the conveyer to tighten 35 said complementary surfaces relative to each other and extending, when in operative position, in parallel with the direction of movement of the conveyer.

2. Means for interconnecting the sections of 40 shaking conveyers comprising an attachment secured to each side wall of a conveyer section at one end thereof, and another attachment secured to each side wall at the other end of the conveyer section co-operable with said first-named attachments of the adjacent element respectively, said 45 attachments extending transversely of said walls and having curved complementary bearing surfaces engaging each other, the axis of curvature of said surfaces extending horizontally and transversely of the direction of movement of the conveyer, and a member provided on both sides of said sections and adapted to tighten 50 said complementary surfaces relative to each other and extending, when in operative position, in parallel with the direction of movement of the conveyer.

3. Means for interconnecting the sections of 55 shaking conveyers comprising an attachment secured to each side wall of a conveyer section at one end thereof, and another attachment secured to each side wall at the other end of the conveyer section comprising a bifurcated portion having hingedly mounted thereon said tightening member, the attachments on the other end of the section terminating in an eye adapted to be engaged by the tightening member of the adjacent section.

3. Means for interconnecting the sections of 60 shaking conveyers comprising an attachment secured to each side wall of a conveyer section at one end thereof, and another attachment secured to each side wall at the other end of the conveyer section co-operable with said first-named attachments of the adjacent element respectively, said 65 attachments extending transversely of said walls and having curved complementary bearing surfaces engaging each other, the axis of curvature of said surfaces extending horizontally and transversely of the direction of movement of the conveyer, and a member provided on both sides of said sections and adapted to tighten 70 said complementary surfaces relative to each other and extending, when in operative position, in parallel with the direction of movement of the conveyer.

walls and having curved complementary bearing surfaces engaging each other, the axis of curvature of said surfaces extending horizontally and transversely of the direction of movement of the conveyer, and a member provided on both sides of said sections and adapted to tighten said complementary surfaces relative to each other and extending, when in operative position, in parallel with the direction of movement of the conveyer, 5 the attachments of one end of said conveyer section comprising a bifurcated portion having hingedly mounted thereon a screw bolt, the attachments on the other end of said section terminating in a slotted eye adapted to be engaged by said screw bolt of the adjacent section.

4. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, said attachments extending transversely of said walls and having curved complementary bearing surfaces engaging each other, the axis of curvature of said surfaces extending horizontally and transversely of the direction of movement of the conveyer, and a member provided on both sides of said sections and adapted to exert a force in the direction of movement of the conveyer to tighten said complementary surfaces relative to each other and extending, when in operative position, in parallel with the direction of movement of the conveyer, 10 said tightening members being mounted on the respective attachments for swinging motion in a vertical and horizontal plane.

5. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, 15 said attachment extending transversely of said walls and having curved complementary bearing surfaces engaging each other, the axis of curvature of said surfaces extending horizontally and transversely of the direction of movement of the conveyer, and a member provided on both sides of said sections and adapted to exert a force in the direction of movement of the conveyer to tighten said complementary surfaces relative to each other and extending, when in operative position, 20 in parallel with the direction of movement of the conveyer, said tightening members being hingedly mounted on the respective attachments by means of a ball joint connection.

6. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, 25 said attachment extending transversely of said walls and having curved complementary bearing surfaces engaging each other, the axis of curvature of said surfaces extending horizontally and transversely of the direction of movement of the conveyer, and a member provided on both sides of said sections and adapted to exert a force in the direction of movement of the conveyer to 30

tighten said complementary surfaces relative to each other and extending, when in operative position, in parallel with the direction of movement of the conveyer, said tightening members being articulated in themselves.

7. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, said attachment extending transversely of said walls and having curved complementary bearing surfaces engaging each other, the axis of curvature 35 of said surfaces extending horizontally and transversely of the direction of movement of the conveyer, and a member provided on both sides of said sections and adapted to tighten said complementary surfaces relative to each other and extending, when in operative position, in parallel with the direction of movement of the conveyer, each of said tightening members comprising a U-shaped yoke pivotally secured to one attachment of one end of said conveyer section 40 and adapted to engage the complementary attachment of the adjacent section and a wedge on said yoke adapted to lock said yoke and said attachment in engaging position.

8. Means for interconnecting the elements of shaking conveyers as specified in claim 7, in which said yoke is hingedly mounted on the respective attachment for swing motion in a horizontal and vertical plane.

9. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, 45 said attachment extending transversely of said walls and having curved complementary bearing surfaces engaging each other, the axis of curvature of said surfaces extending horizontally and transversely of the direction of movement of the conveyer, and a member provided on both sides of said attachment and adapted to tighten said complementary surfaces relative to each other and extending, when in operative position, in parallel with the direction of movement of the conveyer, each of said tightening members being pivotally secured to one of said attachments, the pivoting means simultaneously carrying the running wheels of the conveyer sections.

10. Means for interconnecting the sections of shaking conveyers comprising an attachment secured to each side wall of a conveyer section at one end thereof, and another attachment secured to each side wall at the other end of the conveyer section co-operable with the said first-named attachments of the adjacent element respectively, 50 said attachment extending transversely of said walls and having curved complementary bearing surfaces engaging each other, and a member pivotable around the axis of curvature of said surfaces and secured to each side of said sections, said member being adapted to tighten said complementary surfaces relative to each other and extending, when in operative position, in parallel 55 with the direction of movement of the conveyer.
